United States Patent Office

Des. 183,661
Patented Oct. 7, 1958

183,661

BICYCLE STAND

Clement C. Reetz, Miami Springs, Fla.

Application April 12, 1957, Serial No. 45,713

Term of patent 14 years

(Cl. D90—18)

FIG. 1

FIG. 2

FIG. 3

FIG. 4

Fig. 1 is a top plan view of a bicycle stand, showing my new design, the bottom being substantially plain; Fig. 2 is a right end elevational view thereof; Fig. 3 is a perspective view of Fig. 1; and Fig. 4 is a cross-sectional view on line 4—4 of Fig. 1.
I claim:

The ornamental design for a bicycle stand, substantially as shown and described.
